PAINT SPRAYER

Dan Loe, Simi, Calif.

Application December 28, 1953, Serial No. 400,396

3 Claims. (Cl. 299—86)

This invention relates to a paint sprayer and particularly to such a device which is used in connection with air pressure to apply paint to a surface. After application to the surface, the paint is further spread with a conventional paint brush.

It is an object of my invention to provide a paint sprayer of the class described which sprays the paint onto the surface in solid form and not in a fog, as is conventional with pressure paint sprayers. At the present time, air and paint are mixed under pressure to provide a fine spray. This not only strikes the painting surface, but also spreads into the atmosphere where it contacts other surfaces, which is undesirable. With my invention, the paint is diffused into small particles, but is not broken down into a fog.

It is a further object of my invention to provide a paint sprayer of the class described which will spread the paint over a wider surface than is ordinarily possible with conventional paint sprayers, so that paint can be applied while less work remains to be done to spread the paint after its application.

My invention also comprises such other objects, advantages and capabilities as will later more fully appear and which are inherently possessed by my invention.

While I have shown in the accompanying drawings and described herein a preferred embodiment of my invention, it should be understood that the same is susceptible of modification and change without departing from the spirit of my invention.

Referring to the drawings,

Fig. 1 is a vertical sectional view of my paint sprayer with some parts left in elevation;

Fig. 2 is an end view of my paint sprayer;

Fig. 3 is an enlarged detailed sectional view of the parts enclosed by circle 3 of Fig. 1;

Fig. 4 is a vertical sectional view taken on line 4—4 of Fig. 3;

Fig. 5 is an elevational view with parts in section taken on line 5 of Fig. 3;

Fig. 6 is a perspective view partly broken away of the modification of my shield.

A preferred embodiment which has been selected to illustrate my invention comprises an air blower tube 10, which is attached to an air hose 11 which in turn leads to a blower which is not shown in the drawings. A paint hose 12 is positioned adjacent the air hose 11 and leads to a pressure tank which is also not shown in the drawings. The air blower and pressure tank which are not shown may be any conventional device.

A paint valve 13 comprises a plunger 14, which is adapted to be depressed by the painter. Plunger 14 is normally held in upward position by a coil spring 15. When so held, paint cannot pass through the valve 13, but is blocked by the bottom of the plunger 14. When the plunger 14 is moved downwardly against the pressure of coil spring 15, the path through the paint valve 13 is

2

opened and paint moves through the valve to a paint spraying tip 16.

The paint spraying tip 16 has an end portion 17, the bottom of which has a slit 18, which extends downwardly and forwardly at a slight angle and which extends over an arc which may vary from a small arc to a large arc of 180° or more. Arcs of 90°, 135° and 180° have been successfully used. For purposes of illustration, an arc of 180° has been shown in the drawings.

10 When the paint moves out of the slit 18, it is struck by air which is moving outwardly through the air blower tube 10 under pressure from the blower. The particles of paint are forcibly carried to the painting surface, covering a substantial area.

15 In order to prevent any background movement of the paint and to facilitate spraying the paint over a wide area, a shield 18a may be mounted on the spraying tip 16 directly behind the paint outlet 17. A screw threaded nut 19 holds the shield 18a in place on the spraying tip 16. 20 The shield 18a prevents air from contacting the paint as soon as it leaves the slit 18 and assures that the paint is diffused over a wide area before it is propelled by the air toward the surface being painted.

In operation, the painter connects the paint hose to the pressure tank and then starts the blower. The paint spraying tip 16 is then moved to painting position. When the plunger 14 is moved downwardly by manual pressure, the paint moves through the valve 13 into the spraying tip 16 and out through the slit 18 into the path of air passing

30 through a conical section 20 defining an open end of the air blower tube 10, which air forces the paint against the surface being painted.

It should be noted that with my invention, a fine screen or film of paint is provided across the diameter of the air blower tube transversely to the movement of the air there-

35 through, so that the paint is easily blown onto a wide area of the surface being painted. The paint remains, however, in a more substantial form than a fog and does not spread through the air to fall on other surfaces than the surface being painted.

40 Referring to Fig. 1 of the drawings, this shows one form of my shield 18a. Referring to Fig. 6 of the drawings, this shows a modified form of my shield in which the shield 18a is provided with a circumferential flange which projects forwardly from the shield. The type of flange

45 used in practice depends largely on the type of paint being used and its action in the sprayer.

I claim:

1. In a paint sprayer having a source of paint under pressure and an air blower, a valve connected on one side to said paint source, said valve being manually operable to permit the flow of paint therethrough, an air blower tube having an open end connected to said air blower, a substantially cylindrical paint spraying tip connected to the other side of said valve, said tip being disposed within said air blower tube adjacent said open end, said tip being closed except for a paint outlet comprising a slit extending downwardly and slightly forwardly from the horizontal axis of said tip adjacent the end thereof, said slit comprising an arc extending around part of the circumference of said tip, said valve adapted to permit paint to flow through said valve into said paint tip and out said paint outlet into the stream of air flowing through said air blower tube to be blown against the painting surface over a wide area.

2. The subject matter of claim 1, in which said slit has an arc which is greater than 45°.

3. In a pressure paint spraying device, a paint spraying tip connected at one end to a source of pressure paint supply and closed at its opposite end, said tip having a paint outlet extending downwardly and slightly forward

from the longitudinal axis of said tip, said paint outlet comprising a slit forming a substantial arc around the circumference of said tip, an air blower tube having an open end connected at one end to an air blower, said tip being so positioned with respect to said tube that said paint outlet provides a spray of paint extending transversely into the stream of air flowing out of said tube through said open end. 5
